5 Claims. (Cl. 40—96)

This invention relates to a method of and devices for facilitating the reading of manuscripts.

In general manuscripts are used by speakers such as lecturers and wireless announcers, by the speaker either looking continuously at the horizontal or upwardly inclined manuscript or glancing at it from time to time to prepare himself for a certain amount of freely delivered speech.

In any case the speaker's gaze is removed from the audience either continuously or from time to time, which is undesirable as regards the effect of the speech; further the sound effect varies very considerably because with the change in the direction of gaze the sound direction naturally also changes.

These difficulties are overcome by the method and devices according to the invention.

The method consists in the manuscript or the like being reflected into the horizontal or approximately horizontal direction of gaze of the speaker; it appears between the speaker and the audience in a reflector which neither hides the speaker from the audience nor hinders the speaker himself in any way. The manuscript can be read directly in the reflector by the speaker without his having to turn his direction of gaze or speech away from the audience during his whole speech.

The method can be put into practical effect by a device which reflects the manuscript to the speaker by the aid of a single reflector, the manuscript being written in reverse, or if a normally written manuscript is used an auxiliary, reversing reflector being interposed.

In using a single reflector, the idea of reverse writing and the reading of reversed writing by the aid of reflection is for the first time deliberately used for a definite technical purpose, namely to facilitate the reading out of manuscripts. In this way the result is obtained that the speaker appears to speak freely yet he can keep to his manuscript even word for word.

The use of one reflector and a reversely written manuscript has the particular advantage that there is no loss in brightness due to repeated reflections and that in addition there is no narrowing of the field of view, particularly if a magnifying reflector, for instance an astronomical, spherical reflector of very considerable focal length such as 0.5 metre, 1 metre or even 1.5 metres, is used.

Figures 1 to 5 of the accompanying drawings illustrate diagrammatically and by way of example a reader's desk according to the invention,

the desk of Figures 1 and 2, working on the principle of a single reflector and reversely written manuscript, while the desk of Figure 3 employs a normally written manuscript and a reversing reflector. The desk of Figures 4 and 5 employs a single reflector and reversely written manuscript but the drawings show a funnel-shaped opening within the desk top provided with a microphone on the bottom.

Figure 1 shows the desk partly in elevation and partly in vertical section on the line A—A of Figure 2, while Figures 2 and 3 are both plan views.

In Figures 1 and 2 the casing of the desk is marked 1; the direction of gaze of the speaker is indicated by arrows. On the casing 1 is a reflector 2 which reflects the manuscript into the horizontal direction of gaze of the speaker. The actual reflector 2 is held adjustably by a holder 3 having for example a ball joint 4. The manuscript 5 in reverse writing is in roll form and is unwound from an upper roller 6 to a lower roller 7 and during use is illuminated by a trough lamp 8. The roller 6 projects a little above the horizontal desk top 9 and can be conveniently manipulated by the speaker during his speech to roll off the manuscript. The two rollers 6 and 7 are coupled together for example by a rubber cord 10, so that the speaker can roll and unroll the manuscript at more than one place on the desk. A further operating drum 11 is provided, which is coupled to the roller 7 by another rubber cord 12.

Whether the speaker manipulates roller 6 or drum 11 the desired movement of the manuscript noiselessly takes place.

A carrying frame 13 in which the rollers 6 and 7 are journaled is supported in the desk casing 1 at one end on a bracket 14 on the desk bottom and at the other end at 15 on the rear vertical wall of the desk, whereby the manuscript is held downwardly inclined away from the speaker, for example at an angle of 45°.

The carrying frame 13 with manuscript can at any time be changed for another with another manuscript so that the desk can freely be used by each speaker. The manuscript with reverse writing can conveniently be prepared photographically from a normally written original.

The opening in the desk top 9 in which the manuscript support and feed device freely rests, is marked 16. When the manuscript is illuminated by the lamp 8, the reversed writing of the manuscript 5 appears on the reflector 2 as a forward, upright, virtual image which comprises not

just a few lines but about half a normal sheet of manuscript. By using a concave mirror of suitable focal length the image will be magnified, for example three or four fold.

As the speech progresses the speaker feeds the manuscript from one roller to the other without difficulty.

The device of Figure 3 is identical with that of Figures 1 and 2 except that an auxiliary reversing reflector 17 is provided in order to throw a reversed image of the normally written manuscript into the main reflector 2.

If amplified sound transmission is desired, the microphones are advantageously arranged right and left of the main reflector 2, a smaller number being required than usual because change in the direction of speech delivery by the speaker no longer needs to take place to the degree necessary in the normal mode of use of a manuscript.

The device of Figures 4 and 5 discloses a desk 1 with a funnel-shaped opening 28, whose walls are tapering off. On the bottom of the opening 29a microphone 21 has been provided. Its position is so arranged, that the sounds which are produced in the next neighbourhood of the speaker are prevented from arriving at the interior of the funnel-shaped opening 28 and at the microphone and that only the sounds of the speaker arrive at it. In this wall a small number of microphones, advantageously one microphone, is required. Another improvement is the arrangement of a motor 17, especially of a gramophone motor. This serves for the purpose to move the roller 7. The movement of the roller 7 will be transmitted to the upper roller by a rubber cord 10, by which the two rollers 6 and 7 are coupled. The motor 17 can be started by a pair of switches 18, arranged on both sides of the upper roller 6 and on the horizontal desk top 9. Another switch 19 is provided on the flooring of the speaker's platform. By means of this switch 19 the motor 17 can be started by the foot of the speaker. In the end a movable switch, not illustrated, can be provided which the speaker is allowed to put into his pocket. The arrangement of the other improvements is the like as shown by the Figures 1-3.

Finally it should be mentioned that it is not absolutely essential to use manuscripts in roll form, but that usual manuscripts in pages can be used.

What is claimed is:

1. Apparatus of the class described, comprising a speaker's desk having a well-forming opening therein, a pair of spaced rollers arranged in the opening of said desk and supported at respectively different elevations below the level of the horizontal direction of gaze of the speaker, a manuscript wound at one end on one of said rollers and secured at its other end to the other of said rollers, an endless belt operatively connecting said rollers together to permit progressive pay-off of said manuscript from one roller to the other, and means for reflecting the manuscript into substantially the horizontal direction of gaze of the speaker.

2. Apparatus of the class described, comprising a speaker's desk having a well-forming opening therein, a pair of rollers arranged in the opening of said desk and supported at respectively different elevations below the level of

the horizontal direction of gaze of the speaker, a manuscript wound at one end on one of said rollers and secured at its other end to the other of said rollers, the subject-matter of the manuscript being arranged in reverse writing, said rollers being so arranged that the plane of the manuscript slopes downwardly away from the speaker at an angle of approximately 45°, an endless belt operatively connecting said rollers together whereby said rollers are rotatable in unison, means operatively connected to one of said rollers for paying off the manuscript from one roller to the other, and a mirror adjustably supported on said desk between the speaker and the audience for reflecting the manuscript into substantially the horizontal direction of gaze of the speaker.

3. Apparatus of the class described, comprising a speaker's desk having a substantially vertical well-forming opening, a pair of rollers arranged in the opening of said desk and supported at respectively different elevations below the level of the horizontal direction of gaze of the speaker, a manuscript wound at one end on one of said rollers and secured at its other end to the other of said rollers, said rollers being so arranged that the plane of the manuscript slopes downwardly away from the speaker at an angle of approximately 45°, an endless belt operatively connecting said rollers together, means operatively connected to one of said rollers for paying out the manuscript from one roller to the other, means on said desk for illuminating the manuscript, and means for reflecting the manuscript into substantially the horizontal direction of gaze of the speaker.

4. Apparatus of the class described, comprising a speaker's desk having a substantially vertical well-forming opening, a pair of spaced rollers arranged in the opening of said desk and supported below the level of the horizontal direction of gaze of the speaker, a manuscript wound at one end on one of said rollers and secured at its other end to the other of said rollers, means operatively connecting said rollers together, a reflector adjustably supported on said desk between the speaker and the audience for reflecting the manuscript into substantially the horizontal direction of gaze of the speaker, and a reversing mirror interposed between the manuscript and the reflector.

5. Apparatus of the class described, comprising a speaker's desk having a substantially vertical well-forming opening, a pair of spaced rollers arranged in the opening of said desk and supported at respectively different elevations below the level of the horizontal direction of gaze of the speaker, a manuscript wound at one end on one of said rollers and secured at its other end to the other of said rollers, the plane of said manuscript sloping downwardly away from the speaker at an angle of approximately 45°, means operatively connecting said rollers together, whereby rotation of one of said rollers will rotate the other to cause said manuscript to be paid out from one roller and wound on the other, a reflector adjustably supported on said desk between the speaker and the audience for reflecting the manuscript into substantially the horizontal direction of gaze of the speaker, and a reversing mirror interposed between the manuscript and the reflector.
